UNITED STATES PATENT OFFICE.

DANIEL C. RIPLEY, OF PITTSBURG, PENNSYLVANIA.

DESIGN FOR A BOTTLE.

SPECIFICATION forming part of Design No. 17,243, dated April 5, 1887.

Application filed January 15, 1887. Serial No. 224,498. Term of patent 7 years.

To all whom it may concern:

Be it known that I, DANIEL C. RIPLEY, of Pittsburgh, in the county of Allegheny and State of Pennsylvania, have invented a new

5 and original Design for Glass Bottles and Jars; and I do hereby declare the following to be a full, clear, and exact description thereof, reference being had to the accompanying drawings, in which—

10 Figure 1 is an elevation of a globe-shaped footed bottle or jar embodying my new and original design, and Fig. 2 is a modification.

The characteristic feature of my design consists of the globe-shaped body *b* and a figured ring or neck portion, *a*, surmounted on a zone of the spherical body *b*. The figured portion consists of a raised pattern covering the whole surface of the ring *a*; but the beads *d* may be omitted, as shown in Fig. 2. The 15 body *b* has a foot, *c*. A suitable stopper, *e*, is used with some articles, and with others it is

not. It therefore is not to be considered necessary to my design, which is applicable to bottles, jars, pitchers, and similar footed articles.

25

I claim—

1. The design for footed bottles and jars, consisting of the spherical body *b*, the figured neck-ring *a*, covering a zone of the body *b*, the ring having a raised pattern on its entire surface, as shown and described.

2. The design for footed bottles and jars, consisting of the spherical body, a figured neck-ring, and bead-work round the mouth of the ring, as shown and described.

In testimony whereof I have hereunto set my hand this 31st day of December, A. D. 1886.

DANIEL C. RIPLEY.
